UNITED STATES PATENT OFFICE.

HANS MAHNCKE, OF COLORADO SPRINGS, COLORADO, ASSIGNOR TO THE WOOD PRODUCTS COMPANY, A CORPORATION OF COLORADO.

EXTENSION TABLE.

Application filed April 1, 1922. Serial No. 548,572.

To all whom it may concern:

Be it known that I, HANS MAHNCKE, a citizen of the United States, residing at Colorado Springs, in the county of El Paso and 5 State of Colorado, have invented certain new and useful Improvements in Extension Tables, of which the following is a specification.

This invention relates to tables of the 10 extensible type.

An important object of this invention is to provide a table having a pair of extensible leaves which may be positioned directly beneath the main top when not in use so that 15 the extensible leaves will not in any way interfere with a person sitting at the table.

A further object is to provide an extensible table having simple means whereby the extension leaves are securely supported 20 when extended whereby the same are prevented from sagging.

Another object of this invention is to provide an extension table which is of highly simplified construction, neat in appearance 25 and cheap to manufacture.

Other objects and advantages of the invention will be apparent during the course of the following description.

In the accompanying drawing forming a 30 part of this application and in which like numerals are employed to designate like parts throughout the same,

Figure 1 is a perspective of the improved extension table.

35 Figure 2 is a sectional perspective of the same, the view illustrating the bottom of the table or the underside of the top.

Figure 3 is a bottom plan view of the table.

40 In the drawing wherein for the purpose of illustration is shown a preferred embodiment of the invention the numeral 5 designates the legs of the table, the said legs being connected at their upper ends to the usual side and end cross bars 6 and 6'.

An intermediate strip 7 is permanently connected to the end cross bars 6' at the ends of the table by means of L-shaped brackets 8.

The main top is designated by the numeral 50 10 and is loosely connected to the intermediate strip 7 by means of a pair of guide strips 11 secured to the underside of the

top by means of fastening devices 12. As illustrated in Figure 3 the guide strips 11 of which there are two are received in cut-away portions in opposite sides of the stationary strip 7 whereby the top is held against excessive lateral or endwise movement by the intermediate strip. It will be seen that the ends of the guide strips 11 will contact with shoulders 14 at the ends of the cut-away portions so that the top 10 is prevented from moving longitudinally. Further the top is held against excessive upward movement by means of a cross plate 15 secured to the intermediate portions of the guide strips 11 and extending beneath the intermediate strip. It is thus seen that the top 10 may be moved upwardly until the cross plate 15 engages the under side of the 60 stationary strip 7.

As illustrated particularly in Figure 1 a pair of extension leaves 20 may be positioned beneath the main top 10 and on opposite sides of the strip 7. The extension leaves 20 are preferably of the same thickness as the stationary intermediate strip 7 so that the top 10 will flatly rest on the intermediate strip and the extension leaves. Further when in the position illustrated in 75 Fig. 1 the outer edges of the extension leaves 20 are flush with the outer edges of the top 10 whereby to present a neat appearance.

The extension leaves 20 are rigidly connected to pairs of supporting arms 28 the said supporting arms being secured to the undersides of the leaves and extending for a substantial distance beyond the inner longitudinal edges of the same. Figure 2 85 illustrates that the supporting arms 28 are slidable through openings 29 in the cross bars 6 and that the arms are gradually increased in thickness toward their inner ends so that as the leaves are withdrawn or moved 90 to their extended positions the top 10 will be moved upwardly. That is to say the openings 29 extend out through the upper edges of the cross bars 6 and the supporting arms 28 have engagement with the bottom 95 walls of the openings so that as the leaves 20 are moved outwardly the top as well as the leaves will be moved upwardly. However, when the leaves 20 are moved beyond 100

- the top 10 the top drops down flush with the extension leaves. The inner portions of the arms are confined between the inner edges of the bracket 8 and between guide strips or lugs 35 so that the arms are held against lateral movement. Figure 3 illustrates that the brackets 8 not only connect the intermediate strip 7 to the table but also form guides for the arms 28.
- 10 The outward movement of the leaves 20 is limited by means of stop lugs 43 secured to the under sides of the supporting arms 28 and adapted to engage the inner sides of the cross bars 6.
- 15 In operation the leaves 20 are manually drawn to the position illustrated in dotted lines in Figure 1 whereupon the top 10 will drop and assume a position flush with the leaves. When extended the leaves are securely supported by means of the arms 28 which of course remain in engagement with the intermediate strip 7. When it is desired to return the leaves to the full line position as illustrated in Figure 1 it is merely necessary to move the top 10 upwardly and slide the leaves inwardly.

As illustrated in Figures 2 and 3 the brackets 8 have a holding strip 60 connected thereto, the said holding strip forming a means to secure the arms in position. That is to say the holding strip limits the downward movement of the arms 28.

Having thus described the invention, what I claim is:—

- 35 1. A table comprising cross bars, a stationary strip permanently secured to said cross bars and having its longitudinal edge portions cut away to define shoulders, a movable top having its under side provided with parallel guide strips received in said cut-away portions, the ends of said guide strips being adapted to engage said shoulders whereby to hold the top against endwise movement, and a cross plate secured to said guide strips and adapted to contact with the under side of said stationary strip.
- 40 2. A table comprising cross bars, a stationary strip permanently secured to said cross bars and having its longitudinal edge portions cut away to define shoulders, a top having its under side provided with parallel guide strips received in said cut-away portions, the ends of said guide strips being adapted to engage said shoulders whereby to hold the top against endwise movement, and a cross plate secured to said guide strips and adapted to contact with the under side of said stationary strip, extension leaves slidable beneath said top and having arms engaging said stationary strip.
- 45 3. A table comprising cross bars, a stationary strip permanently secured to certain of said cross bars and having its longitudinal edge portions cut away to define shoulders, a top having its under side provided with parallel guide strips received in said cut-away portions, the ends of said guide strips being adapted to engage said shoulders whereby to hold the top against endwise movement, and a cross plate secured to said guide strips and adapted to contact with the under side of said stationary strip, extension leaves slidable beneath said top and having arms

parallel guide strips received in said cut-away portions, the ends of said guide strips being adapted to engage said shoulders whereby to hold the top against endwise movement, a cross plate secured to said guide strips and adapted to contact with the under side of said stationary strip, extension leaves slidable beneath said top and having arms engaging said stationary strip, and stop lugs secured to the under sides of said arms and engaging certain other of said cross bars.

4. A table comprising cross bars, a stationary strip permanently secured to certain of said cross bars and having its longitudinal edge portions cut away to define shoulders, a top having its under side provided with parallel guide strips received in said cut-away portions, the ends of said guide strips being adapted to engage said shoulders whereby to hold the top against endwise movement, a cross plate secured to said guide strips and adapted to contact with the under side of said stationary strip, extension leaves slidable beneath said top and having arms engaging said stationary strip, stop lugs secured to the under sides of said arms and engaging certain other of said cross bars, and guide lugs secured to the under side of said stationary strip and holding said arms against lateral movement.

5. A table comprising cross bars, a stationary strip permanently secured to certain of said cross bars and having its longitudinal edge portions cut away to define shoulders, a top having its under side provided with parallel guide strips received in said cut-away portions, the ends of said guide strips being adapted to engage said shoulders whereby to hold the top against endwise movement, a cross plate secured to said guide strips and adapted to contact with the under side of said stationary strip, extension leaves slidable beneath said top and having arms engaging said stationary strip, stop lugs secured to the under sides of said arms and engaging certain other of said cross bars, guide lugs secured to the under side of said stationary strip and holding said arms against lateral movement, and brackets securing said stationary strip to said second mentioned cross bars and cooperating with said guide lugs in holding the arms in position.

6. A table comprising cross bars, a stationary strip permanently secured to certain of said cross bars and having its longitudinal edge portions cut away to define shoulders, a top having its under side provided with parallel guide strips received in said cut-away portions, the ends of said guide strips being adapted to engage said shoulders whereby to hold the top against endwise movement, a cross plate secured to said guide strips and adapted to contact with the under side of said stationary strip, extension leaves slidable beneath said top and having arms

engaging said stationary strip, stop lugs secured to the under sides of said arms and engaging certain other of said cross bars, guide lugs secured to the under side of said stationary strip and holding said arms against lateral movement, brackets securing said stationary strip to said second men-

tioned cross bars and cooperating with said guide lugs in holding the arms in position, and a holding strip secured to said brackets 10 and holding the arms against downward movement.

HANS MAHNCKE.
